Atty

UNITED STATES PATENT OFFICE.

CHARLES H. CHRISTIE, OF BUTLER, PENNSYLVANIA.

DOOR FOR GLASS-POT FURNACES.

Application filed April 15, 1922. Serial No. 552,827.

To all whom it may concern:

Be it known that I, CHARLES H. CHRISTIE, a citizen of the United States, and resident of Butler, in the county of Butler and State 5 of Pennsylvania, have invented a new and useful Improvement in Doors for Glass-Pot Furnaces; and I do hereby declare the following to be a full, clear, and exact description thereof.

10 My invention relates to doors for glass pot furnaces or other furnaces to which it may be found applicable.

The object of my invention is to provide a door formed of refractory material of 15 durable construction in which the irons forming the frame for the raising and lowering of the door are protected from the heat, thereby duly preventing the burning out of the irons and greatly increasing the life of 20 the door.

In the accompanying drawing, Fig. 1 is a front view of a door embodying my invention; Fig. 2 is a top view; Fig. 3 is an end view; and Fig. 4 is a section on the line 25 4—4, Fig. 1; Fig. 5 is a section on the line 5—5, Fig. 1.

In the drawing the numeral 2 designates the door which is made up of refractory material capable of withstanding the intense 30 heat to which such doors are subjected, more especially in the case of glass pot furnaces where the pots are arranged in the furnace and charged with batch by a ladle introduced through the charging opening 3 formed in said door.

To provide for the raising and lowering 40 of the door, an iron framework is necessary, and by my invention this frame-work consists of the lower rod 4 which is embedded in the door and which extends from one end of the door to the other. This rod 4 is exposed at the recesses 5 formed in the door, and the upright rods 6 are secured to the rod 4, said upright rods having the inwardly extending ends with the eye 7 formed to encircle the rod 4.

The upright rods 6 extend up on the outside of the door, and at their upper ends pass through the staples 8 which are held in place 50 by the upper cross bar 9 which extends through said staples and is embedded in the door. The upper ends of the upright rods 6 have the hooks 10 formed thereon with which the lifting chains 11 are connected which pass up over suitable sheaves

which are operated by any suitable power for raising and lowering the door.

The front of the door is formed with the recess 12 which is above the large opening 3, and at this recess a pipe 13 surrounds 60 the rod 9 to protect it at that point from burning or warping.

The lower portion of the door bulges out, as at 14, below the charging opening 3 to form the shelf 15.

By my invention I provide for the protecting of the irons of the frame to which connection is made for the lifting of the door, and the severe action of the heat on said frame is practically eliminated so that 70 the life of the frame is greatly increased as well as the life of the door.

What I claim is:

1. A furnace door comprising a body portion, made up of refractory material, longitudinally extending metal rods embedded in said refractory material, said rods being exposed for a portion of their length near the ends thereof, and upright rods on the outside of said door engaging said rods at 80 the exposed portions, and connecting means at the upper ends of said rods for attaching lifting chains.

2. A furnace door comprising a body portion formed of refractory material, longitudinally extending metal rods embedded in said material adjacent the top and bottom of said door, said rods being exposed for a portion of their length near the ends thereof, upright rods having eyes at the lower 90 ends engaging said longitudinally extending rods at their exposed portions, staples engaging the upper longitudinally extending rods at their exposed portions, and the upper ends of said upright rods passing through 95 said staples, and hooked portions on the upper ends of said upright rods.

3. A furnace door comprising a body portion of refractory material and longitudinally extending metal rods embedded in said material adjacent the top and bottom thereof, said door having a charging opening and a recess formed above said charging opening, across which the upper of said rods extends and a protecting covering for said 100 rod where exposed at said recess, said rods being exposed at, or near, their ends, and upright rods engaging said longitudinally extending rods at their exposed portions.

4. A furnace door comprising a body por- 110

tion of refractory material and longitudinally extending metal rods embedded in said material adjacent the top and bottom thereof, said door having a charging opening and a recess formed above said charging opening, across which the upper of said rods extends, and a pipe surrounding said rod

where exposed at said recess, said rods being exposed at, or near, their ends, and upright rods engaging said longitudinally extending rods at their exposed portions.

In testimony whereof I, the said CHARLES H. CHRISTIE, have hereunto set my hand.

CHARLES H. CHRISTIE.
